(57) **CLAIM**

The ornamental design for a connector terminal as shown and described.

DESCRIPTION

FIG. 1 is a front elevational view of a connector terminal showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof;

FIG. 10 is a rear, left, and top side perspective view thereof;

FIG. 11 is an enlarged view of FIG. 1; and,

FIG. 12 is an enlarged view of FIG. 2.

The broken line showing of the connector terminal is for the purpose of illustrating portions of the article and forms no part of the claimed design.
